ELECTRICAL HEATING DEVICE

Eugene R. Ziegler, Spencerport, N. Y., assignor to
 Ritter Company, Inc., Rochester, N. Y., a corporation of Delaware

Application September 16, 1944, Serial No. 554,394

9 Claims. (Cl. 219—39)

1

This invention relates to electrical heating devices, and, more particularly, to those of smaller size adapted to be quickly and conveniently energized for heating instruments and materials, such as employed, for example, in the practice of the dental and medical professions.

One object of the invention is to provide an improved device of the above character of a more efficient, economical and convenient nature.

Another object is to provide such a device adapted for use instead of the Bunsen burner heretofore commonly employed by practitioners in the dental and medical professions.

Another object is to provide a heating device of the nature indicated comprising an electrical heating element adapted to be quickly energized and to rapidly produce an intense heat.

A further object is to provide such a device capable of being conveniently and economically energized as, for example, by the mere pressure thereagainst of an instrument to be heated, during the heating period only.

Still a further object is to afford such a device provided with means for completely protecting the operator, as well as the operating parts against injury.

Still a further object is the provision of a device such as described in a construction capable of being readily and economically manufactured and assembled and of being readily taken apart for cleaning and reassembled in use.

To these and other ends the invention resides in certain improvements and combinations of parts, all as will be hereinafter more fully described, the novel features being pointed out in the claims at the end of the specification.

In the drawings:

Fig. 1 is a side elevation of a device embodying the present invention and illustrating the same as applied to a dental equipment stand;

Fig. 2 is a top plan view of the device shown in Fig. 1, but detached from the equipment stand;

Fig. 3 is an enlarged, sectional elevation of parts of the device in association with a diagram of the electrical connections;

Fig. 4 is an enlarged, sectional elevation of the device with portions broken away and showing the parts in inactive position;

Fig. 5 is a view similar to Fig. 4, but showing the parts in energizing position;

Fig. 6 is a section on the line 6a—6a in Fig. 5, showing the energizing switch and means for operating the same;

Fig. 7 is a side elevation showing the intermediate section of the base of the device detached;

2

Fig. 8 is an enlarged view similar to Fig. 4, but in a plane at right angles thereto;

Fig. 9 is a view substantially on the line 9a—9a in Fig. 8, and

Fig. 10 is a top plan view of the intermediate section of the base shown in Fig. 7.

The embodiment of the invention herein disclosed by way of illustration, is one adapted for use in place of the Bunsen burner or other gas heater commonly provided on the known stands employed in the dental and medical fields for supporting a variety of equipment within convenient reach of the operator.

Referring more particularly to Fig. 1, there is shown at 15 the branching arm of a dental equipment stand, having pivoted thereon at 16 a swinging arm 17, on the outer free end 18 of which is pivotally mounted a sleeve-like hub 19, of a second swinging arm 20, on which is mounted the usual instrument table 21. In this known type of construction, a Bunsen burner has been commonly incorporated in the vertical pivotal axis of said hub 19, conveniently close to the instrument table. In accordance with the present invention, an electrical heating device is located in the same advantageous position, on the vertical pivotal axis of the outer arm close to the table, as shown in Fig. 1, and hereafter described.

Referring to Fig. 4, the sleeve-like hub 19 on the table arm is journaled on a hollow, vertical trunnion 22, extending upwardly from the end of arm 17, a screw 23 in the hub having its inner end loosely engaged in a groove 24 in the trunnion to prevent inadvertent removal. Arm 20 has its intermediate portion enlarged to form a box-like casing 25, for a transformer 26, which may be of any known and suitable type, such, for example, as commonly employed with neon signs to furnish high voltage current. Hub 19 has an opening 27, for the passage of conductors to and from the transformer and the hub has an upwardly extended, open end 28, for supporting the heating device proper, which will now be described.

The heating device comprises, preferably, a generally cylindrical base portion, formed in several separable sections, mounted on the upper end of the hub and provided at its upper end with a heating element enclosed within one or more housing shells, through the open top of which the heat is applied to the article to be heated.

The base preferably comprises three superposed sections, 29, 30 and 31, of rubber, plastic, or other known or suitable moldable, insulating material. Section 29 rests on the upper end of

hub 19, to which it is secured by screws, as hereafter described. This section is hollowed out in an irregular shape, to receive the switch 32 and the switch actuating frame or spider 33, which will be more fully described hereafter. Section 29 has molded therein spaced high tension conductors, 34 and 35, extending longitudinally therethrough at opposite sides and having their ends projecting above the section and provided with connecting plug ends, 36 and 37.

The intermediate section 30 of the base comprises a body portion 38, Fig. 7, having depending opposite skirts 39, overlying the sides of the bottom section 29 opposite the high tension conductors 34 and 35, to increase the protection against outward sparking between the meeting faces of the adjacent sections. Molded in section 30 are conducting sockets, 40 and 41, Figs. 4 and 5, engaging the conducting plugs 36 and 37 of the high tension conductors, each plug and its socket being preferably formed with a coacting ridge or groove, as shown at 42, to frictionally hold the sections together. The sockets 40 and 41 are fixed to socket sleeves, 43 and 44, extending upwardly above the ends of bosses, 45 and 46, formed on the top end of the section 30, as shown.

The upper base section 31 is of generally plate shape with its bottom face formed with recesses receiving the tapered upper ends of the bosses 45 and 46, which are adapted to wedge in the recesses and frictionally hold the parts together. The bottom face 47 of section 31 abuts upon shoulders, 48 and 49, of bosses 45 and 46, so as to be retained in spaced relation above the upper face 50 of portion 38 of the intermediate section 30, to preserve an air duct 51 between the sections, for the purpose hereafter described. The bottoms of the recesses in the lower face of section 31 are further recessed to receive the upper ends of the conducting sleeves 43 and 44, and have molded therein a pair of conducting plugs, 52 and 53, the lower ends of which are slotted for resiliency, and frictionally and detachably engaged in the said sleeves. Plugs 52 and 53 are fixed at their upper ends to the outwardly bent ends of a pair of spaced, metal strip electrodes, 54 and 55 diverging upwardly above the base for supporting thereacross a high voltage arc. These electrodes are made of any known and suitable material adapted to resist burning by the arc.

It is evident from the above description that the base comprises the three sections, 29, 30 and 31, which, with their respective conducting portions, are detachably connected together, with the high voltage connections extending continuously through the sections, when assembled, from top to bottom of the base. The intermediate section 30 is more positively secured to the bottom section 29, and both sections to the hub 19, by means of oppositely disposed screws, 56 and 57, Fig. 8, which are passed through the portion 38 of the middle section 30, through the lower section 29, and screwed into threaded holes in the bosses formed on the walls of the hub 19. On removal of the upper section 31, however, these screws may be removed and the sections 29 and 30 separated and detached, when necessary.

A housing is provided for the electrodes 54 and 55, comprising an inner refractory shell 58 and an outer metal shell 59, Figs. 4, 5 and 8, having the general shape of a truncated cone and spaced from each other, as shown. Inner shell 58 is preferably seated and supported at its lower edge in a recess in the top face of the base and protected by asbestos facing strips, 60 and 61. These

shells may be made of other materials, if desired, those mentioned having been found highly satisfactory for the purpose.

For transmitting upwardly the heat generated by the electric arc, inner shell 58 has an upper opening 62, preferably in its top surface, above the electrodes, and the outer shell 59 has a similar registering opening 63 formed in an inwardly turned top flange 64 at its top.

Outer shell 59 of the housing is movably supported on the base, preferably by connection with means for actuating the switch controlling the electric circuit, so that downward pressure on the top of the outer shell serves to actuate the switch. To this end, the side walls of the outer shell are fixed by means of short screws 65, Figs. 6 and 9, to the outer ends 66 of the arms of a frame or spider 33, movably housed in the hollow lower section 29 of the base. The spider is preferably made of rubber, plastic, or other known or suitable plastic material, and has molded in its upper face a pin 68, sliding loosely in a socket in the middle section 30, to guide the spider for a short vertical movement. The lower face 69 of the spider, Fig. 8, is arranged to bear against an actuating button 70 in the top of the casing of the spring actuated switch 32, the button normally occupying an upper position corresponding to the open position of the switch and the inactive position of the heater. The switch is preferably of the type known commercially as a "Switchette," manufactured and sold by the General Electric Company, and having the construction hereafter described. The switch spring has sufficient strength to normally hold the spider 33 and the outer shell 59 in the upper position of the latter, shown in Figs. 4 and 8, and the shell may be pressed downwardly on the switch button and move the switch to closed position, the parts then having the position shown in Fig. 5, with the flange 64 of the outer shell coming to rest against the top of the inner shell 58.

The said switch comprises opposite pairs of spaced contacts 71 and 72, Fig. 8, and a resilient conducting plate 73 has its opposite ends provided with contacts 72a playing between the pairs of contacts, 71 and 72, respectively. Plate 73 is cut and formed to provide upwardly inclined, resilient portions 74, engaged by spring fingers 75, depending from the button 70, so as to normally hold the button elevated and the plate contacts 72a in engagement with the lower contacts 72 which in this instance are not connected in circuit. When the button is depressed, however, plate portions 74 are depressed, with the result that the stability of shape of the plate is overcome and its ends snap upwardly and engage and electrically connect the terminals 71 connected in the circuit of the device, so as to close the circuit and energize the heating element. Upon release of the pressure on outer shell 59, however, plate 73 springs back into normal shape so that its ends lie against the lower terminal 72, and its portions 74 raise the button, the spider and the shell to upper, inactive position in which the circuit is broken between the contacts 71.

Switch 33 has terminals 76, Fig. 6, connected in series in one of the conductors 77 connecting the low voltage side of the transformer with the service power line, as shown in the circuit diagram, Fig. 3. Any other known or suitable spring actuated switch may be employed, of course, but I have found the commercially available switch described above to be highly satisfactory for the purpose.

It will be seen that the high voltage conductors are fully insulated in the material of the base, while the electrodes are protected by air gaps and enclosed within both the refractory inner shell 58 and the outer shell 59, so that the operator is fully protected against electrical shock. However, as a further safeguard, it is preferred to locate in the upper opening 62 of the inner shell a conducting ring 78, Fig. 8, to which is connected a conducting wire 79 having a coiled spring portion 80 and extending loosely at its lower end 81 through an opening in the upper base section 31. Conductor 81 projects sufficiently below the section to press against the head of one of the screws 56 screwed at its lower end into the metal hub 19 of the grounded equipment stand, so as to prevent the occurrence of any high voltage conditions at the top of the inner shell.

The arc generated between the electrodes is supplied with a current of air by means of one or more lower openings 82, Figs. 1 and 8, which, when the outer shell is depressed to close the switch, register directly with the air duct 51 between sections 30 and 31 of the base. From this duct a central opening 83 leads through upper base section 31 to a point below and between the electrodes. Additional air for this purpose may enter between the base and the spaced walls of the shell 59 at its lower end.

As appears from the above description of the construction, the outer shell 59 may be slightly depressed by any suitable means, as by downward pressure on an instrument to be heated laid across its upper end. By such downward movement of the shell, the spider 33 is depressed to spring the switch plate into connecting contact with the upper terminals 71 of the switch, to bridge the latter and thus close the circuit including the electrodes and the high tension side of the transformer. A sufficiently high voltage is employed, in relation to the gap between the electrodes, as well understood in the art, to immediately create an arc between the electrodes, heating the air and establishing an upward current past the arc and through the upper openings 62 and 63 of the housing. Such upward air current sweeps the arc upwardly to the upper ends of the electrodes and carries a portion of the arc, or at least a volume of air intensely heated thereby, upwardly through the openings, as indicated in Fig. 5, for direct contact with the instrument or material to be heated and located above or across the top of the outer shell. The device is conveniently operated, therefore, by merely a slight downward pressure on the top of the outer shell, as by means of the same hand of the operator which holds the instrument or material to be heated, so as to obviate any special manipulation and it is quickly energized and produces an intense heating action. This efficient action is obtained, furthermore, by a device which is self-contained and compact, occupying the position and substantially the same space as the gas burner which has been commonly employed for such purposes.

Notwithstanding the employment of high voltage current, the construction is such as to fully safeguard the operator against any possibility of shock. The parts of the device are so constructed and arranged that they may be readily and economically manufactured and assembled and as readily detached and separated for cleaning or repair, as may be found desirable from time to time in use. The device is economical in

operation since it is energized only during the relatively brief intervals of actual use.

It will thus be seen that the invention accomplishes its objects, and while it has been herein disclosed by reference to the details of a preferred embodiment, it is to be understood that such disclosure is intended in an illustrative, rather than a limiting sense, as it is contemplated that various changes in the construction and arrangement of the parts will readily occur to those skilled in the art, within the spirit of the invention and the scope of the appended claims.

I claim:

1. An electrical heating device comprising a housing having an air passage therethrough provided with inlet and outlet openings, means movably associated with said housing having a portion located above said outlet opening thereof and formed to receive an article to be heated, spaced electrodes in said housing below said outlet opening thereof, an electrical circuit including said electrodes and a source of high potential current, switch means controlling said circuit, and a connection between said article receiving means and said switch means for actuating said switch means by the movement of said receiving means.
2. An electrical heating device comprising a housing having an air passage therethrough provided with inlet and outlet openings, means movably associated with said housing having a portion located above said outlet opening thereof and formed to receive an article to be heated, spaced electrodes in said housing below said outlet opening thereof, an electrical circuit including said electrodes and a source of high potential current, switch means controlling said circuit, a connection between said article receiving means and switch means, and spring means for raising said receiving means and opening said switch, said switch being closed by the depression of said receiving means by the engagement therewith of an article to be heated.
3. An electrical heating device comprising a housing having an air passage therethrough provided with inlet and outlet openings, means movably associated with said housing having a portion located above said outlet opening thereof and formed to receive an article to be heated, an electrical transformer, spaced electrodes in said housing below said outlet opening, an electrical circuit including said transformer and electrodes, switch means for controlling said circuit, a connection between said article receiving means and switch means, and spring means for raising said receiving means and opening said switch, said switch being closed on depression of said article receiving means by the engagement therewith of an article to be heated.
4. An electrical heating device comprising an inner housing having an air passage therethrough provided with inlet and outlet openings, an outer housing movably associated with and enclosing said inner housing and having a portion located above said outlet opening thereof and formed to receive an article to be heated, an electrical transformer, spaced electrodes inaccessibly enclosed in said inner housing below said outlet opening thereof and connected in the secondary circuit of said transformer, a switch connected in the primary circuit of said transformer, an actuating connection between said outer housing and switch, and spring means for raising said outer housing and opening said switch, said outer housing being depressed to close said switch by

the engagement therewith of an article to be heated.

5. An electrical heating device comprising a housing having a base, an inner refractory shell on the base, an outer shell movably mounted on said base and enclosing and spaced from said inner shell, said shells having registering upper openings therein, spaced electrodes on said base in said inner shell below said openings, an electrical circuit including said electrodes and a source of high potential current, and a switch actuated by the movement of said outer shell for closing said circuit to produce a heating arc across said electrodes.

6. An electrical heating device comprising a base of insulating material, an inner refractory shell on said base, an outer shell movably mounted on said base and enclosing and spaced from said inner shell, said shells having registering upper openings therein, spaced electrodes on said base in said inner shell and below said openings, an electrical circuit including said electrodes and a source of high potential current, a switch actuated by the movement of said outer shell for closing said circuit to produce a heating arc across said electrodes below said openings and a grounded conducting ring on said inner shell about said opening therein.

7. An electrical heating device comprising a base of insulating material formed by a plurality of separable sections having spaced conductors extending therethrough, an inner shell of refractory material on said base, an outer shell movably mounted on said base and enclosing and spaced from said inner shell, said shells having upper registering openings therein, spaced electrodes on said base in said inner shell below said upper opening thereof and connected with said conductors, an electrical circuit including said conductors and a source of high potential current, a switch in said base for controlling said circuit and actuated by the movement of said outer shell, said base having a lower opening therein for supplying a current of air to said electrodes and carrying the heat from said arc upwardly through said shell openings.

5 8. An electrical heating device comprising a housing having a base, an inner shell on said base and an outer shell movably mounted on said base and enclosing and spaced from said inner shell,

10 said shells having registering upper openings, an electrical transformer, spaced electrodes inaccessibly enclosed in said inner shell below said openings and connected in the secondary circuit of said transformer, switch means connected in the primary circuit of said transformer, an actuating connection between said outer shell and switch means, and a spring for raising said outer shell and opening said switch, said outer shell being depressed to close said switch by the engagement therewith of an article to be heated at said outlet opening.

15 9. An electrical heating device comprising a base of insulating material formed by separable upper and lower sections, separable conductors 25 extending therethrough, an inner shell of refractory material on said upper section, an outer shell movably mounted on said base and enclosing said inner shell, said shells having inlet and outlet openings, an electrical transformer having its secondary circuit connected with said conductors, spaced electrodes inaccessibly enclosed in said inner shell and connected with said conductors, a switch in the primary circuit of said transformer, a connection between said outer shell and said switch, and spring means for raising said outer shell and opening said switch, said outer shell being depressed to close said switch by engagement therewith of an article to be heated at said outlet opening thereof.

EUGENE R. ZIEGLER.
